[57] CLAIM

The ornamental design for a tire lift, as shown and described.

DESCRIPTION

FIG. 1 is a partial perspective view of a tire lift showing our new design, with an automobile tire, automobile and automobile jack in broken lines for illustrative purposes only and forming no part of the claimed design; FIG. 2 is a top plan view thereof; FIG. 3 is a bottom plan view thereof; FIG. 4 is a right side elevational view thereof; FIG. 5 is a left side elevational view thereof; FIG. 6 is a front elevational view thereof; FIG. 7 is a rear elevational view thereof; FIG. 8 is a top side perspective view of the tire lift in its folded position; and, FIG. 9 is a front, opposite side perspective view of the tire lift in its folded position.
